UNITED STATES PATENT OFFICE.

GEORGE P. HORAN, OF RUTLAND, VERMONT.

TRAIN CONTROL.

Application filed May 19, 1923. Serial No. 640,204.

To all whom it may concern:

Be it known that I, GEORGE P. HORAN, a citizen of the United States, and a resident of Rutland, in the county of Rutland and State of Vermont, have invented a new and Improved Train Control, of which the following is a full, clear, and exact description.

The present invention relates to new and useful improvements in train control and it pertains more particularly to means for automatically operating the engineer's valve in order to give an operation of the brakes.

It is one of the primary objects of the invention to provide a new and improved mechanism for moving the engineer's valve to either service or stop position.

It is a further object of the invention to provide a new and improved mechanism for selectively moving the engineer's valve to service or stop position dependent upon track conditions.

It is a further object of the invention to provide a new and improved mechanism which is controlled by roadside signals.

It is a further object of the invention to provide a new and improved mechanism which in addition to being controlled by roadside signals, is operated by the main reservoir pressure of the air brake apparatus of a railway train.

It is a still further object of the invention to combine with the engineer's valve, means for operating the engineer's valve, which means at the same time permits of independent operation of the engineer's valve.

With the above and other objects in view, reference is had to the accompanying drawings, in which—

Figure 1 is a view in elevation, partly in section, showing the position of the apparatus carried by the train and its relation to certain apparatus carried by the roadside;

Fig. 2 is a view in elevation showing the roadside signal, the roadside ramp, the collector carried by the train, and a convenient mounting for the operating mechanism of the engineer's valve;

Fig. 3 is a detail sectional view of the engineer's valve-operating mechanism;

Fig. 4 is a detail plan view showing the manner in which the engineer's valve is operated, and in dotted lines the service position of such valve;

Fig. 5 is a detail sectional view of a portion of the engineer's valve operating mechanism and showing the manner in which it is latched or retained in operative position;

Fig. 6 is a detail elevational view of the current collector carried by the train;

Fig. 7 is a vertical sectional view thereof taken on the line 7—7 of Fig. 6;

Fig. 8 is a detail elevational view of the collector taken at right angles to Fig. 6; and Figure 9 is a plan view of the ramp rail.

Referring more particularly to the drawings, the invention comprises the combination of pressure actuated mechanical means for operating the engineer's valve, and electrically operated means for controlling the operation of the pressure actuated mechanism means for controlling the engineer's valve. Of the two mechanisms, the pressure actuated mechanical means for operating the engineer's valve will be described first.

This pressure actuated mechanical means (see Figs. 3, 4 and 5) comprises a pneumatic valve 10, an electro-pneumatic valve 11, and a power cylinder 12. The pneumatic valve 10 is formed of two members 13 and 14, having screw-threaded engagement, as at 15, and such members 13 and 14 form two chambers 16 and 17, respectively. Mounted in the chamber 16, is a valve member 18, provided with a valve stem 19 adapted to engage with a seat 20 formed in the bottom of the chamber 16. Leading from the bottom of the chamber 16, is a passage 21, and connected to the lower end of the pneumatic valve 10, is a pipe 22, which pipe is connected, as at 23, to one end of the power cylinder 12. Interposed between the ends of this pipe 22, is a valve 24, the purpose of which will be hereinafter described.

The reference character 25 designates a pipe leading from the main reservoir, and

such pipe contains the main reservoir pressure. Leading from this pipe 25, is a pipe 26, the latter pipe communicating with the chamber 16 heretofore mentioned through the medium of a passage 27. Leading from the pipe 25, is a pipe 28, connecting with the electro-pneumatic valve 11 by means of a passage 29.

The electro-pneumatic valve 11 heretofore mentioned comprises a valve chamber 30, and mounted therein is a valve member 31 having passages 32 and 33.

Leading from the valve chamber 30 of the electro-pneumatic valve to the chamber 17 of the pneumatic valve, is a pipe 34, and such pipe is adapted to have communication with the pipe 28 heretofore mentioned through the medium of the passage 32 in the valve member 31 of the electro-pneumatic valve 11. Leading from the chamber 17 of the pneumatic valve 10, is a pipe 35, and said pipe 35 communicates with the interior of the valve chamber 30 of the electro-pneumatic valve 11, by means of a passage 36. At a point diametrically opposite the passage 36, a vent opening 37 is provided.

Pivots mounted, as at 38, on the chamber 30, of the electro-pneumatic valve 11, is a manually operated lever 39, and connected to the lever 39, as at 40, is a lever 41, which lever 41 is in turn pivotally connected, as at 42, to a member 43 secured to the upper end of the valve 31 of the electro-pneumatic valve 11. This member 43 forms an armature for an electro-magnetic member 43' which will be hereinafter more fully described since it forms a part of the electrical mechanism. Pivots connected, as at 40', to the manually operated lever 39, is another lever 44, and pivotally connected to the lever 44, as at 45, is still another lever 46, which last lever operates a valve 47. This valve 47 is mounted in the upper end of a pipe 48, which in turn is connected, as at 49, to one end of the power cylinder 12, and serves as a bleed for said power cylinder.

Mounted within the power cylinder 12, is a piston 50. This piston has a rod or stem 51 projecting through the end 52 of the power cylinder 12, and the extremity of said rod or stem 51 is forked, as indicated at 53. Surrounding the rod or stem 51 of the piston 50 and interposed between the head of the piston 50 and the end wall 52 of the power cylinder 12, is a coil spring 54, the purpose of which will be hereinafter described. The reference numeral 55 designates the handle of the engineer's brake valve, and such handle is provided with a depending portion 56 having a right-angularly disposed extension 57 with which the forked end of the stem or rod 51 of the piston 50 engages. This right-angular extension 57 is provided with a roller 58 in order to reduce friction in the engagement

between the forked end 53 of the stem or rod 51 and the handle of the engineer's valve. The mechanism so far as described is that which serves to move the engineer's brake valve to service position.

The means by which an emergency set is had is shown in Fig. 5. In such figure, the reference character 60 designates a pipe in the brake pipe pressure line, and carried by the end of this pipe 60, is a valve chamber 61. Mounted in this valve chamber 61, is a valve member 62, provided with a passage 63 therethrough. The valve chamber 61 is provided with a vent opening 64 in line with a passage 65 by means of which the pipe 60 communicates with the interior of the chamber 61.

The valve member 62 has an extension 66, and mounted on said extension is a member 67, which forms the armature for the electromagnet 68. Pivots connected, as at 69, to the valve housing 61, is a manually operated lever 70, and pivotally connected to this manually operated lever 70, as at 71, is a link 72, which in turn is pivotally connected as at 73, to the extension 74 of the armature 67.

The mechanism for giving a service application of the brakes operates in the following manner:

As the parts are shown in Figs. 3 and 4, there is no application of the brakes, the engineer's valve being shown in release position. With the several parts in this position, main reservoir pressure is admitted to the chamber 16 by means of the pipe 25, pipe 26 and passageway 27. Main reservoir pressure is also admitted to the chamber 17 by way of the pipe 25, pipe 28, passages 29 and 32, and pipe 34. The presence of main reservoir pressure in the chambers 16 and 17 balances the valve 18. Main reservoir pressure is also present in the pipe 35 and the passage 36. When the valve 18 is balanced, the valve 19 engages the seat 20 and closes the passage 21 to the pipe 22. When the parts are in this position, the valve 47 is in open position, thus venting the power cylinder 12. This position of the parts permits the piston 50 to move to the extreme left in Fig. 3, under the influence of the spring 54, and the piston is shown in this position in Fig. 3. At this time the valve 31 of the electro-pneumatic valve 11 is in the down position shown and its passage 33 is out of register with the passage 36, thereby preventing an escape of the main reservoir pressure from the chamber 17 of the pneumatic valve 10.

Assuming now that the electro-pneumatic valve member 43' is energized, the armature 43 is attracted, which moves the member 31 to a position where its passage 33 registers with the passage 36 and the passage 37. As the passage 33 registers with the passages

36 and 37, the main reservoir pressure present in the chamber 17 is exhausted to the atmosphere. Immediately the valve 18 becomes unbalanced and moves in the chamber 16 to a point where its valve member 19 disengages the seat 20, thus opening the pipe 22 to the cylinder 16. When the pipe 22 is in communication with the chamber 16 of the pneumatic valve 10, the main reservoir pressure passes through the pipe 22 to the power cylinder 12, moves the piston 50 to the right in Fig. 3, and moves the engineer's valve handle 55 to the service application shown by dotted lines and designated by the reference character A in Fig. 4, thus giving a service application of the brakes of the train.

It will be noted that the valve 47 is shown in open position. This valve, however, is moved to closed position by the movement of the valve 31 and the armature 43 through the medium of the links 41, 44, and the lever 46. To maintain the valve 31 in this position, a suitable locking member 75 is provided, which comprises two spring fingers between which a head member 76 carried by the armature 43 is adapted to pass and be retained thereby, thus holding the valve member 31 in brake-applying position. To overcome this position, the manually operated lever 39 is depressed, which breaks the engagement of the head 76 with the spring finger 75 and moves the member 31 so that its passage 33 is out of register with the passages 36 and 37, and moves the valve 47 to open position. When the valve member 31 is moved to the point where its passage 33 is out of register with the passages 36 and 37, the passage 33 moves into register with the pipes 28 and 34 and thus main reservoir pressure is again admitted to the chamber 17 and the valve 18 again becomes balanced and closes the passage 21. As the valve 47 is moved to open position, the pipe 22 and the power cylinder 12 are vented, and under the influence of the spring 54 the piston 50 moves to the left in Fig. 3, and the entire mechanism is ready for a subsequent operation. It is to be understood, however, that the engineer's valve 55 is preferably not positively connected to the forked end 53 of the stem or rod 51, and said engineer's valve, therefore, would be moved to releasing position manually.

The emergency mechanism operates in the following manner:

With the parts in the position shown in Fig. 5, the escape of air from the brake pipe 60 is prevented by the valve member 62. When, however, the electro-magnetic member 68 is energized the armature 67 is attracted thereby and the member 62 is moved to a position where its passage 63 will register with the passages 64 and 65, and thus

permit of an escape of air from the brake pipe pressure line, and cause an emergency application of the brakes. As the armature 67 is attracted by the electro-magnetic member 68, the head member 77 is engaged between the two resilient members 78, and the member 62 is maintained in the position where its passage 63 registers with the passages 64 and 65.

To release the emergency application, it is necessary for the engineer or other operator to depress the manually operated lever 70, which through the medium of the link 72, returns the member 62 to the position shown in Fig. 5, and prevents an exhausting of the brake pipe pressure. This operation disengages the head member 77 from the resilient fingers 78, and the device is then set for a subsequent operation.

Referring to Fig. 2 of the drawings, it will be noted that the electro-magnetic member 43' is adapted to be energized by electromagnets 80. One of the electromagnets 80 is connected to the ground 81 by means of a conductor 82. Leading from the other electromagnet 80 is a conductor 83, connected to a collector 84 in the form of a shoe. As more clearly shown in Fig. 6, this collector 84 comprises two conductor sections 85 and 86, which are insulated from each other by the insertion of suitable non-conducting material 87. It is the conductor section 86 with which the conductor 83 is connected through the medium of a suitable binding post 88.

Referring again to Fig. 2, it will be noted that the electro-magnetic member 68 is energized by two electromagnets 89 and one of such electromagnets 89 is connected to the conductor 82 leading to the ground 81, by means of a conductor 90. The other electromagnet 89 is connected by means of a conductor 91, to the conductor section 85 of the collector shoe 84, by means of a binding post 92 or the like. While this collector shoe may be carried at any position on the train, it is preferably supported by one of the trucks of the tender and the support of said collector shoe is yielding in order that a more perfect contact may be had between the shoe and the element from which it collects current. To provide for this yielding contact, a bracket 100 is secured to the truck in any desired manner, and carried by said bracket and depending therefrom is a guide member 101. This guide member 101 is secured to the bracket by means of bolts, or the like, 102. Slidably mounted in the guide member 101 is a stem or bolt 103, and secured to the lower end of said stem or bolt 103 is a plate 104. This plate 104 is secured to the stem 103 by means of nuts 105, the stem 103 having a reduced portion 106 upon which the plate is received.

The upper end of the stem or bolt 103 is reduced, as at 107, and is extended above the bracket 100, as shown.

The plate 104 heretofore mentioned carries a housing 108, and mounted within the housing 108 and surrounding the guide member 101, is a coil spring 109. Threaded on the housing 108, as at 110, is a cap plate 111, and such cap plate is adapted to compress the spring upon downward movement of the housing 108 and stem 103. The reference character 112 designates a housing carried by the housing 108, and said housing 112 has telescoping engagement with the housing 113 dependent from a guide member 101. These two housings 112 and 113 are adapted to exclude the weather from the spring 109 and its associated parts. The spring is secured between the cap plate 111 and the plate 104, by means of a threaded ring, or the like, 114.

In order to limit the movement of the stem or bolt 103, the same is provided with a notch 115, and mounted in the notch 115, is a key 116, which slides in a slot 117 formed in the guide member 101. The key 116 prevents the stem or bolt 103 from turning, and, consequently, insures the collector 84 being in the proper position at all times.

The collector 84 is secured to the movable plate 104 by means of bolts, or the like, 118, and said collector 84 is positioned at right angles to the mechanism described as the support thereof. This collector 84 is adapted to contact with the ramp rail 119 mounted alongside the track, and said ramp rail is supported by suitable brackets 120. The under face of this ramp rail is curved as designated by the reference character 121, and it will be noted that the collector 84 heretofore referred to is arcuate in cross-sectional form in order to facilitate a good riding contact between the collector 84 and the ramp 119. As more clearly shown in Fig. 9 the ramp 119 has two conductor sections 122 and 123.

The reference character 125 designates a roadside signal, and said roadside signal has a semaphore arm 126 pivotally connected thereto as at 127. Suitably supported by the roadside signal 125 are contact members 128 and 129. The contact member 128 is connected with the conductor section 122 of the ramp 119 by means of a conductor 130, and the contact member 129 is connected to the conductor section 123 of the ramp rail 119 by means of a conductor 131. Carried by the semaphore arm 126, is a switch member 132, and said switch member has two contacts 133 and 134, so arranged upon the semaphore arm that when the same is in "caution" position, the contact 133 will engage the contact 129, and when the semaphore arm is in "danger" position, the contact 134 will engage the con-

tact 128. The "caution" position of the semaphore arm is designated in Fig. 2 by the reference character B, and the "danger" position of said semaphore arm is designated in the same figure by the reference character C.

Leading from the switch member 132 is a conductor 135, and such conductor is in turn connected to a suitable source of power 136 in the form of a storage battery, which battery is grounded as indicated at 137.

Assuming now that the train is approaching a block the entrance to which is marked by the roadside signal 125, and assuming further that beyond the block marked by the roadside signal 125, which block the train is about to enter, there is a "danger" condition. The semaphore 126 of the roadside signal 125 would be set to the position indicated by the reference characters B or "caution". This setting of the semaphore 126 may or may not be automatic since the operation of the apparatus herein described is not dependent upon the type of roadside signal but is capable of use with all conventional roadside signals. With the semaphore 126 in the position indicated by the reference character B, the contact member 133 engages the contact member 129. As the train approaches the roadside signal 125 and the collector 84 engages the ramp rail 119, a circuit is completed as follows:

From the source of power 136, through conductor 135, contact 133 of the switch member 132, contact 129, conductor 131, to the conductor section 123 of the ramp rail 119. From the ramp rail 119, the current passes through the conductor section 86 of the collector 84 as the collector engages the ramp rail, and from the conductor section 86 of the collector the current passes through the conductor 83 to the electromagnets 80, and by way of the conductor 82 to the ground 81. This circuit energizes the electromagnets 80 and attracts the armature 43 thereof, and a service application of the brakes is had in the heretofore described manner.

Under the service application the train may proceed under the control of the engineer, but upon reaching the next roadside signal, which would be set at "danger" unless the danger condition has been removed, a circuit would be completed as follows. It being understood as heretofore stated, that the semaphore arm 126 would be in the dotted-line position designated by the reference character C in Fig. 2.

With the semaphore arm 126 in this position, the circuit is complete from the source of power 136, through conductor 135, contact 134 of the switch arm 132, contact 128, conductor 130, to the conductor section 122 of the ramp rail 119.

As the collector 84 passes beneath the

ramp rail 119, the circuit passes through the conductor section 85 of the collector through the conductor 91, electromagnets 89, and by way of conductors 90 and 82 to 5 the ground 81. This attracts the armature 68 of the electromagnets 89 and gives an emergency application of the brakes in the manner heretofore described.

From the foregoing it is apparent that the 10 present invention provides a new and improved control mechanism for trains. Further, it will be noted that the mechanism is automatic in its operation but requires manual re-setting of the parts, thus greatly 15 adding to the factor of safety of the device since it is impossible to have the device automatically reset falsely.

What is claimed is:

1. In an apparatus of the class described, 20 a power cylinder, a piston associated therewith and adapted to operate an engineer's brake valve, and means for introducing the pressure of an air brake system to said power cylinder to operate its piston, said 25 means comprising a balanced valve, an electrically operated valve, electrical means for operating said electrically operated valve, mechanical means for holding said valve in its operated position, and manually 30 operated means for resetting said electrically operated valve after an operation thereof has been had.

2. In a system of train control, a power 35 cylinder for operating an engineer's brake valve to move the same to service position, a balanced valve for admitting main reservoir pressure of the air brake system of the train to said power cylinder, said balanced 40 valve in its balanced position preventing supply of main reservoir pressure to the power cylinder, means for disturbing the balance of said valve, said means comprising an electrically operated valve, electrical means for operating said electrically operated valve, 45 manually operated means for re-setting said electrically operated valve after an operation thereof has been had, and means for venting the power cylinder simultaneously 50 with the re-setting of said electrically operated valve.

3. In an air brake system, a cylinder, a piston in the cylinder and connected with the engineer's valve, a balanced valve connected with said cylinder, means for introducing 55 the pressure of an air brake system to one side of the valve, an electrically operated valve, means for introducing the pressure of air through the electrically operated valve to the other side of the balanced valve, 60 means for venting the balanced valve through the electrically operated valve, means for locking the valve in its operative position, and means for resetting the said valve.

4. In an air brake system and in combination with the engineer's valve thereof, a motor for operating the engineer's valve, said motor comprising a cylinder having each of its ends open to the atmosphere, a piston 65 connected at one end to the engineer's valve and having a head movable through said cylinder, a second valve, said second valve being of the balanced type, a piston in the second valve, means for admitting train-line pressure to opposite sides of the piston to 70 balance the same, means for establishing communication between said balanced valve and the cylinder of the engineer's valve motor, a valve associated with the balanced 75 valve for closing said communication means, means for disturbing the balance of the balanced valve to open the valve associated therewith and admit train-line pressure to the cylinder of the engineer's valve motor to 80 give an operation of the engineer's valve, and means for automatically and simultaneously closing the atmospheric communication of one end of said motor cylinder.

5. In an air brake system, a cylinder, a 85 piston in the cylinder and connected with the engineer's valve, a valve casing having a valve seat in its bottom, a piston in the casing and having a stem provided with a valve, a pipe leading from the valve seat of 90 the casing to said cylinder, a main pressure pipe connected with the valve casing below the piston thereof, a second valve casing with which the main pressure pipe is connected and having a vent opening, a pipe 95 connecting the valve casing with the first valve casing above its piston, a pipe connecting the upper side of the said valve casings, an electrically operated valve in the second valve casing and controlling the 100 passage of air to the first valve casing and from said casing to the vent opening of the second casing.

6. In an air brake system, a cylinder open 105 to the atmosphere at each end, a spring 110 pressed piston in the cylinder and having its piston rod connected with the engineer's valve, a valve casing having a valve seat in one end, a pipe connecting the valve seat with the cylinder, a piston in the valve 115 casing and having a stem provided with a valve, a main pressure pipe connected with the lower end of the valve casing below its piston, a second valve casing having a vent opening, a pipe connecting the pressure pipe 120 with the second valve casing, a pipe connecting the lower end of the second valve casing with the upper end of the first valve casing above its piston, a pipe connecting the upper 125 ends of the valve casings, and an electrically operated valve in the second valve casing, said valve having transverse ports, one for the passage of air pressure to the first valve

casing and the other for establishing communication between the first valve casing and the vent of the second valve casing.

7. In an air brake system, a cylinder having an opening in one end, a vent pipe leading from the other end of the cylinder, and provided with a valve, a spring pressed piston in the cylinder and having its piston rod connected with the engineer's valve, a balanced valve connected with said cylinder, means for introducing the pressure of air brake system to one side of the valve, an

electrically operated valve, means for introducing the pressure of air to the other side of the valve through the electrically operated valve, means for venting the balanced valve through the electrically operated valve, means for locking the electrically operated valve in its operative position, means for resetting said valve, and means for operating the valve of the vent pipe of the cylinder from the resetting means. 15 20

GEORGE PAUL HORAN.
